[57] **CLAIM**

The ornamental design for an electronic game housing, as shown and described.

DESCRIPTION

FIG. 1 is a perspective view of the electronic game housing showing our new design;

FIG. 2 is a top plan view thereof;

FIG. 3 is a right side elevational view thereof, the left side elevational view being substantially identical thereto;

FIG. 4 is a front elevational view thereof, the rear elevational view being substantially identical thereto; and

FIG. 5 is a bottom plan view thereof.
